PRINTING PLATE INKER

Charles G. Dudis and Robert F. Du Bois, Dayton,
Ohio, assignors to The National Cash Register
Company, Dayton, Ohio, a corporation of
Maryland.

Application July 13, 1951, Serial No. 236,562

6 Claims. (Cl. 118—253)

1

This invention relates to improvements in inking means for printing plates.

This invention is directed to a means to reink printing members such as printing members made of microporous rubber, and particularly ink-impregnated porous rubber stamps of the type now widely used for printing labels for merchandise, such as, for example, meat sold at self-service meat stands. The labels may be produced by an accounting machine which prints various data, such as the weight of the merchandise, the price per pound, the total price, and the name of the article. With the exception of the name of the merchandise, the above data is usually set up on the keyboard of the accounting machine. The large number of different kinds of merchandise to be labeled makes it impractical to set up the names of the articles automatically from a keyboard. For this reason, the merchant is provided with a rack of name-printing plates which can be selectively inserted into the accounting machine, prior to its operation, to cause the proper name to be printed on the label. To avoid complicated inking means, such as a ribbon, the name plates are constructed of ink-impregnated micro-porous rubber, and a large number of legible prints can be obtained from such an ink-impregnated printing plate before it becomes necessary to reink the plate.

It is an object of the present invention to provide a novel reinking means for such printing members.

A specific object of the invention is to provide an ink-dispensing container having an ink pad which can be moistened periodically by squeezing the container, in combination with a movable receptacle for the printing member, which receptacle can be controlled in its movement to direct the printing member into contact with the moistened ink pad in such a way as to control the pressure of contact with the moistened pad to most effectively reink, or recharge, the porous printing member with ink.

With these and incidental objects in view, the invention includes certain novel features of construction and combinations of parts, a preferred form or embodiment of which is hereinafter described with reference to the drawing which accompanies and forms a part of this specification.

In the drawing:

Fig. 1 is a side elevation of the reinker shown partly in cross section to show its interior construction.

Fig. 2 is a sectional view taken on line 2—2 of Fig. 1, and looking in the direction of the arrows.

2

Fig. 3 is a sectional view showing the printing member in contact with the moistened pad, taken on line 3—3 of Fig. 5, looking in the direction of the arrows.

Fig. 4 is a top plan view of the reinking means, shown with the printing member out of the device.

Fig. 5 is a top plan view of a part of the reinking device and shows the printing member therein, and is shown with the lid in chain lines for clarity.

Fig. 6 is a side elevational view of the reinking device, shown in reduced scale.

General description

Described in general terms, the invention consists in providing a fluid-dispensing container with a hinged receptacle at the top thereof which is adapted to receive a printing plate consisting of a micro-porous rubber type member mounted on a rigid plate. The face of the type is faced downwardly, and, upon rocking the hinged receptacle downwardly, the face of the type is brought into contact with an ink-moistened pad carried at the upper end of a tube projecting into a reservoir of ink. The receptacle is provided with a diaphragm which is pressed inwardly to force ink up the tube and into the pad to moisten the pad when needed. A stop for the hinged receptacle limits the movement of the printing member to control the contact pressure between the face of the type and the moistened pad. A suitable stop is also provided to properly locate the printing member in the receptacle. The receptacle is mounted within a housing on the top of the dispenser, and the housing includes a slidable and removable cover, so that access can be had to the inside of the housing when it is desired to inspect or clean the pad.

Detailed description

As illustrated herein, a can, which has a substantially rectangular cross section, is provided, and said can has compressible side walls 20 and 21, end walls 22 and 23, a bottom 24, and a top 25 with a threaded neck 26 extending upwardly therefrom. A cap screw 27, screwed on the neck 26, seals the ink in the can.

The top 25 has secured thereto a drop pipe 28 extending between the top 25 and into a reservoir of ink 29, said pipe terminating near the bottom 24 of the can.

The pipe 28 provides a means of communication between the ink 29 and the under side of an ink pad 30 (see Fig. 3), to which ink is forced by squeezing the diaphragm 31, which forces the fluid up the inside of the pipe 28 and into the pad 30. Thus the pad can be kept at the desired de-

gree of saturation. The pad can be made of any known material which is ink-absorbing.

The pad 30 is secured to the top 25 by two clips 32 and 33, at the ends thereof. The clips are formed in the shape of a U and have reduced portions overlying the ends of the pad, as clearly shown in Fig. 4. The clips 32 and 33 are secured to dams forming cross walls 34 and 35, respectively, by any means such as soldering, spot welding, etc. The dams 34 and 35 are flanged at their bottoms, by means of which they are secured to the top 25 of the can. Each end of the walls is also flanged, by means of which they are secured to side walls 36 and 37 (see Fig. 4) to form a rigid frame. The dams provide means for keeping the ink in a restricted area in the can, thus preventing leaking of ink outside the desired area.

The side walls 36 and 37 are formed with their front edges slanting slightly inwardly at their top edges, and their top edges are slanted downwardly toward the rear edges. The side walls 36 and 37 are connected by a wall 38, which wall may be a separate piece soldered to the side walls 36 and 37, or, if desired, the side walls and the wall 38 can be formed of one piece of metal. The front ends of the side walls 36 and 37 are connected by a front wall 39.

The walls 36, 37, 38, and 39 all have flanges formed on their lower edges, which rest on the top 25 of the can and form a convenient means for soldering the walls to the top 25, to provide a fluid-tight compartment on the top of the can. A bleed hole 40 (Fig. 4) in the top 25 provides a means for excess ink to flow back into the can. The bleed hole 40 is located beneath the ink pad 30.

The side walls 36 and 37 are provided with openings, which support a shaft 43 between them. Spacers 41 and 42 are supported on the shaft 43, and spring clips 19 (Fig. 5) are mounted in grooves in the shaft 43 to side-space extensions 44 and 45, respectively, of a pivoted receptacle 46. The spring clips 19 also act to maintain the ends of the shaft 43 in the openings in the side walls 36 and 37, in which the shaft is mounted. The front end of the receptacle is flared upwardly at 47 to guide a printing member support 48 into the receptacle.

The receptacle 46 is formed downwardly at an angle, as at 49 (Fig. 2), on each side an extent equal to the thickness of the printing member support 48, and then horizontally at each side to a point adjacent the side walls 36 and 37, leaving a sufficient distance to permit free movement of the receptacle between said side walls. Secured to each horizontal section of the receptacle 46 is a plate 50, which plates extend inwardly toward each other so as to extend below the printing member support 48. The plates 50 are provided with flares 51, which, together with the flare 47, guide the printing member into position between the under side of the receptacle 46 and the top sides of the plates 50, thus providing a guideway for the printing member.

The side walls 36 and 37 are provided with flanges 56 and 57, respectively (Fig. 2), and grooves, formed by bending a slidable lid 58 (shown in chain lines in Fig. 5) inwardly at each side thereof, engage and slide on said flanges. Stops 59, formed on the forward end of the lid 58, limit the sliding movement of the lid when positioned thereon, thus forming an enclosure for the compartment formed by the walls 36, 37, 38, and 39. The stops 59 engage the wall 39 when the lid is in closed position.

The wall 38 is provided with a suitable opening 60, through which the printing member support 48 is inserted when the support is moved into position in the receptacle. The support 48 is provided with a locating stud 61, movable in a notch 62 in the receptacle, and in a notch 63 in the lid 58. Thus the support 48 is located in operating position by stud 61 and the notch 62, which locks the lid in position as long as a printing member 10 is in normal position in the receptacle.

The receptacle 46 is normally held upwardly in contact with the under side of the lid 58 by a coil spring 65 supported on shaft 43 having one end bearing on the can top 25 and its other end 15 engaging the extension 44 of the receptacle. The spring 65 is tensioned to maintain the support upwardly in engagement with the under side of lid 58. When the lid 58 is removed from the flanges 56 and 57, the spring 65 moves the receptacle into 20 the substantially vertical position shown by the chain lines in Fig. 1. The exact chain-line position is governed by the engagement of the support with the inner side of wall 38, as shown in Fig. 1. When the receptacle is in the chain-line position, 25 the ink pad 30 is in exposed position for inspection, cleaning, or other service needed.

The printing member support 48 has secured thereon a micro-porous printing plate 70. Printing members of this class absorb a large quantity 30 of ink by contact with a supply. However, the contact pressure must be regulated. To this end, the bottom of the opening 60 is used as a stop for 35 arresting the support 48, as illustrated in Fig. 3. To further control proper contact conditions between the printing member 70 and the pad 30, the pad is thicker at the point of contact with the printing member. See Figs. 1 and 3, where the thickest section of the pad is indicated at 71.

Operation

The reinking device above described is used in systems where a plurality of printing elements are used in machines such as cash registers and accounting machines. In some uses, a plurality of printing impressions are made from the printing element in succession. The printing members are particularly adapted for use in labeling food, such as meat, for self-service markets. In such use, the butcher cuts and packages meat 45 of the same kind for an indefinite period. When he is preparing to cut sirloin steak, for example, he selects the printing member with the type characters spelling "Sirloin steak" from a rack on which they are stored, and inserts it into the 50 label-printing machine. The cut of meat, such as sirloin steak, is then weighed, and the weight is set up on the keyboard of the machine; then the price per pound and the total price are set up on the keyboard. Then the machine is operated to issue a label containing the above data 55 together with the name "Sirloin steak." This operation is repeated as long as sirloin steak is being weighed and packaged. It is only when the butcher begins cutting, weighing, and packaging another kind of meat that the printing member is 60 removed from the label-printing machine and another substituted therefor.

Since many impressions must be made from the inserted printing member after one insertion, it 65 is readily seen that the printing member must be capable of storing a large supply of ink and that it becomes necessary to resupply the printing member periodically.

When it is necessary to resupply ink to the 70 printing member, it is inserted in the receptacle

46, and the diaphragm 31 is pressed in to force ink to the pad 30, if the pad does not already have a sufficient supply of ink therein. Any excess of ink is confined between the dams 34 and 35 until this excess can bleed back into the can through bleed hole 40.

After it is determined that the pad 30 is sufficiently moistened, the operator depresses the printing member support 48 with his finger, as illustrated in Fig. 3, to rock the receptacle and the printing member around its pivot shaft 43 until the printing member is arrested by coming into contact with the top of the opening 60. When this position is reached, the face of the porous rubber type is in proper contact with the thicker section of the pad 30 to cause the porous rubber to absorb ink from the surface of the pad. It is sometimes necessary to "pump" the printing member up and down a few times to permit capillary action to resupply the surface of the pad 30 with ink for the printing member to absorb.

Release of the operator's finger permits the support 48 to be retracted by spring 65 until arrested by the lid 58, when the printing member can be withdrawn from the receptacle 46. By referring to Figs. 2 and 4, it can be observed that the opening 60 enlarges laterally near its upper end. This enlarged section of the opening 60 permits insertion of the support into the receptacle, and, when the support is lowered by the operator, a shouldered section of the support passes behind the wall 39 to prevent shifting of the support during its downward movement and also prevents removal of the support until it reaches its uppermost position.

The shape of opening 60 also makes it necessary for the operator to fully insert the support 48 until the stud 61 strikes the notch 62 in the receptacle 46 before the support and the printing member can be depressed, thus assuring complete contact of the printing characters with the pad 30, so that the printing characters will be uniformly inked.

When it is desired to inspect the pad 30 or service the receptacle in any manner, the slideable lid is removed from the device, which permits the receptacle to be moved out of the way and into the position shown by chain lines in Fig. 1, as hereinbefore described.

What is claimed is:

1. In a device of the class described, the combination of a fluid chamber, a fluid-wettable pad mounted on said chamber, a pipe connecting the interior of the chamber with said pad whereby fluid is transmitted from the chamber to the pad, a pivoted receptacle mounted on said chamber adapted to receive a porous printing member when in retracted position, said receptacle and printing member being manually movable on the pivot of the receptacle to move the printing member into contact with the pad, said porous printing member capable of absorbing fluid from the pad when in contact therewith, means to limit the pivotal movement of the receptacle to control the contact pressure between the printing member and the pad, and resilient means to restore the receptacle to original position upon release thereof, to thereby maintain the receptacle in a position wherein the printing member is out of contact with the pad while being withdrawn from, or inserted into, the receptacle.

2. In a device of the class described, the combination of a fluid chamber, a fluid-wettable pad mounted on said chamber, a pipe connecting the

interior of the chamber with said pad whereby fluid is transmitted from the chamber to the pad, a housing mounted on the fluid chamber, a shaft carried by the walls of the housing, a receptacle pivoted on said shaft, a coil spring on said shaft having one end in contact with the chamber and another end in contact with the receptacle to bias the receptacle away from the chamber, a guideway in the receptacle adapted to receive a porous printing member, a stop in the guideway to arrest the porous printing member when it is located in line with the pad, said receptacle being pivotally movable on the shaft to move the porous printing member into contact with the fluid-wet surface of the pad to enable the porous printing member to absorb fluid from the pad, and means to control the contact pressure between the pad and the porous printing member.

3. In a device of the class described, the combination of a fluid chamber, a fluid-wettable pad mounted on said chamber, a pipe connecting the interior of the chamber with said pad whereby fluid is transmitted from the chamber to the pad, a housing mounted on the fluid chamber, a shaft carried by the walls of the housing, a receptacle pivoted on said shaft, a coil spring on said shaft having one end in contact with the chamber and another end in contact with the receptacle to bias the receptacle away from the chamber, a guideway in the receptacle adapted to receive a porous printing member, a stop in the guideway to arrest the porous printing member when it is located in line with the pad, said receptacle being pivotally movable on the shaft to move the porous printing member into contact with the fluid-wet surface of the pad to enable the porous printing member to absorb fluid from the pad, means to control the contact pressure between the pad and the porous printing member, and a removable lid for the housing to render the receptacle and the pad accessible for servicing.

4. In a device of the class described, the combination of a fluid chamber, a fluid-wettable pad mounted on said chamber, a pipe connecting the interior of the chamber with said pad whereby fluid is transmitted from the chamber to the pad, a housing mounted on the fluid chamber, a shaft carried by the walls of the housing, a receptacle pivoted on said shaft, a coil spring on said shaft having one end in contact with the chamber and another end in contact with the receptacle to bias the receptacle away from the chamber, a guideway in the receptacle adapted to receive a porous printing member, a stop in the guideway to arrest the porous printing member when it is located in line with the pad, said receptacle being pivotally movable on the shaft to move the porous printing member into contact with the fluid-wet surface of the pad to enable the porous printing member to absorb fluid from the pad, means to control the contact pressure between the pad and the porous printing member, a plurality of dams surrounding the pad to restrict flow of fluid away from the pad, and an opening in the chamber within the confines of the dams to drain excess fluid into the chamber.

5. In a device of the class described, the combination of a fluid chamber, a fluid-wettable pad mounted on said chamber, a pipe connecting the interior of the chamber with said pad whereby fluid is transmitted from the chamber to the pad, a pivoted receptacle mounted on said chamber adapted to receive a porous printing member having a reduced portion, said receptacle and printing member being manually movable on the

pivot of the receptacle to move the printing member into contact with the pad, said porous printing member capable of absorbing fluid from the pad when in contact therewith, means to limit the pivotal movement of the receptacle to control the contact pressure between the printing member and the pad, a housing for the receptacle mounted on the fluid chamber, and an opening in the housing through which the porous printing member can be inserted when the porous printing member is inserted into the receptacle, said opening being wider at the point of insertion of the porous printing member and narrower below such point whereby the housing maintains the porous printing member in proper alinement in the receptacle when the printing member is moved into contact with the pad, and said narrower section of the opening preventing withdrawal of the porous printing member until the printing member is restored adjacent the wider section of said opening.

6. In a device of the class described, the combination of a fluid chamber, a fluid-wettable pad mounted on said chamber, a pipe connecting the interior of the chamber with said pad whereby fluid is transmitted from the chamber to the pad, a pivoted receptacle mounted on said chamber adapted to receive a porous printing member having a shoulder, said receptacle and porous

printing member being manually movable on the pivot of the receptacle from an original position to move the printing member into contact with the pad, said porous printing member capable of absorbing fluid from the pad when in contact therewith, means to limit the pivotal movement of the receptacle to control the contact pressure between the porous printing member and the pad, resilient means to restore the receptacle to said original position upon release thereof, to thereby maintain the receptacle in a position wherein the porous printing member is out of contact with the pad while being withdrawn from, or inserted into, the receptacle, and a housing for the receptacle having an opening therein adapted to coat with the porous printing member, a slot therein in which the printing member moves, said shoulder on the printing member movable behind the walls of the slot to lock the printing member in the housing at any position other than said retracted position.
